UNITED STATES PATENT OFFICE.

EDWARD J. BROOKS, OF EAST ORANGE, NEW JERSEY, ASSIGNOR TO E. J. BROOKS & CO., OF NEW YORK, N. Y.

DRESS-WEIGHT.

SPECIFICATION forming part of Letters Patent No. 269,154, dated December 12, 1882.
Application filed July 21, 1882. (No model.)

To all whom it may concern:

Be it known that I, EDWARD J. BROOKS, a citizen of the United States, residing at East Orange, in the State of New Jersey, have invented a new and useful Improvement in Dress-Weights, of which the following is a specification.

This invention, like another of the same name described and claimed by me in my specification forming part of an application for patent filed on the 15th day of July, 1882, is an improvement on certain leaden "weights" of crude forms heretofore used by ladies or by dress-makers in the manufacture of ladies' apparel for the purpose of compelling certain parts of such apparel to hang as desired.

My present invention consists, first, in an annular-disk "dress-weights," each disk having a large central orifice, which provides for quickly and securely fastening each disk in place by means of a few central stitches, in lieu of stitching around each weight, as heretofore, or across attaching-strips, as in my other invention aforesaid, or, in addition to the latter, with an attaching-piece of textile fabric crossing its large central orifice, so that the fastening-stitches may take hold of this in attaching the dress-weight to the lining only or to single or unlined parts; secondly, in an annular-disk dress-weight provided with an attaching-piece of textile fabric crossing its large central orifice, and flattened to secure said attaching-piece within a collapsed stringing-hole parallel to the faces of the disk, the flattening of the disk serving also to render it thin and of increased diameter, so that it shall not cause the outer fabric to bulge, as hereinafter more particularly specified.

In the drawings which accompany this specification, Figure 1 is a perspective view, and Figs. 2 and 3 are sections, of one of the primary leaden castings used in producing the preferred form of my annular-disk dress-weights; and Figs. 4 and 5 are face views, Fig. 6 an edge view, and Fig. 7 a section on the line 77, Fig. 5, illustrating the preferred mode of manufacture and final shape; and Fig. 8 is a face view, and Fig. 9 a section, of another of my an-

nular-disk dress-weights, illustrating a modification.

Like letters of reference indicate corresponding parts in the several figures.

In carrying out my invention I prefer to first cast in sufficient quantity annular disks A, of lead or equivalent soft metal, of the form represented by Figs. 1, 2, and 3 and at the left-hand end in Figs. 4 and 6, with a large central orifice, o, in each, and with a "flat" transverse stringing-hole, h, parallel to the faces of the disk, each extending through the disk, and readily formed in the mold with the aid of a core-bar for said hole h. Such disks A are strung by hand or machinery upon continuous lengths of ordinary textile tape, B, as illustrated by Figs. 4 and 6, and the disks are next flattened by rolling, pressing, or stamping them successively, as illustrated at the right-hand end in said Figs. 4 and 6. Finally, the tape B is cut between the disks, either by the manufacturer or by the retailer or user, and the severed disks A, (one or more,) with the portion of tape belonging to them, are ready for their use as dress-weights, as illustrated by Figs. 5 and 7, the said tape constituting within the central orifice, o, of each disk an attaching-piece most effectively located, as a few stitches at this point, as represented at s, Fig. 5, fasten the disk in place tightly, while said attaching-piece is securely held on opposite sides of said orifice by the walls of the collapsed stringing-hole h of the flattened disk, and the flattening of the latter improves it for its purpose by rendering it thinner (and no less heavy) and increasing its diameter, as hereinbefore set forth.

In the modification illustrated by Figs. 8 and 9 my annular-disk dress-weights, for use in the same manner as single weights produced in the manner above described, are cast in complete form, (or cast and punched,) with supplemental sewing-holes x around the central orifice, o, as a substitute for an attaching-piece, to receive the central stitches, as shown at s, Fig. 8.

I do not claim herein a dress-weight consisting of a disk or disks and an attaching-strip, as

this is the subject of my previous application for patent aforesaid. Neither do I claim herein the within-described preferred mode of manufacture; but I reserve the right to claim this in another application to be filed hereafter.

I claim as new and of my present invention—

1. An annular-disk dress-weight having in its disk A a large central orifice, *o*, and provided with an attaching-piece, B, of textile fabric, crossing said orifice and secured within the disk, substantially as herein described, for the purpose set forth.

2. An annular-disk dress-weight having in its disk A a large central orifice, *o*, and a transverse stringing-hole, *h*, and provided with an attaching-piece, B, of textile fabric, within said stringing-hole, said disk being flattened, as described, for the purposes set forth.

EDWARD J. BROOKS.
